(57) **CLAIM**

The ornamental design for an agitation device, as shown and described.

DESCRIPTION

FIG. 1 is a perspective view of an agitation device showing the new design.

FIG. 2 is a top view of the agitation device.

FIG. 3 is a side view of the agitation device; and,

FIG. 4 is a bottom perspective view of the agitation device. The broken lines in the drawings depict unclaimed environmental subject matter.
